(57) **CLAIM**

The ornamental design for a slope screen spray system, as shown and described.

DESCRIPTION

FIG. 1 is a perspective view of a first embodiment of a slope screen spray system in a sieve system in accordance with the present invention;

FIG. 2 is an enlarged view of section 2 of FIG. 1;

FIG. 3 is an enlarged view of section 3 of FIG. 1;

FIG. 4 is a top view of the slope screen spray system in a sieve system of FIG. 1;

FIG. 5 is an enlarged view of section 5 of FIG. 4;

FIG. 6 is a front view of the slope screen spray system in a sieve system of FIG. 1;

FIG. 7 is an enlarged view of section 7 of FIG. 6;

FIG. 8 is a left side view of the slope screen spray system in a sieve system of FIG. 1;

FIG. 9 is an enlarged view of section 9 of FIG. 8;

FIG. 10 is a back view of the slope screen spray system in a sieve system of FIG. 1;

FIG. 11 is a perspective view of the back of the slope screen spray system in a sieve system of FIG. 1;

FIG. 12 is a detailed view of section 12 of FIG. 11;

FIG. 13 is a right side view of the slope screen spray system in a sieve system of FIG. 1;

FIG. 14 is an enlarged view of section 14 of FIG. 13; and,

FIG. 15 is a bottom view of the slope screen spray system in a sieve system of FIG. 1.

Broken lines show environmental structure and are not parts of the claimed design. They may be present or absent with the claimed design.
